APPARATUS FOR CONVERTING TOW TO TOP

Robert Heme de Lacotte and Emmanuel Teissier,
Paris, France, assignors to Societe de Constructions Mecanique de Stains, a corporation of France

Application October 30, 1951, Serial No. 253,872
In France August 23, 1951

5 Claims. (Cl. 19—0.37)

1

This invention relates to a process and apparatus for converting a bundle or tow of continuous filaments into a sliver or top of staple fibers, and more particularly to a method and apparatus in which the conversion is produced by stretching the bundle to breakage between a set of feed rollers and a set of stretching rollers, the latter set operating at a substantially higher rate.

In systems of this type the length of the staple fibers produced corresponds in general to the spacing between the two sets of rolls although a considerable number of short fibers are also produced which impair the quality of the yarn spun therefrom. Long periodic irregularities are also observed which produce irregularities in thickness of the yarn formed by drafting and twisting the sliver or top.

The process that forms the subject matter of the present invention involves imposing upon the bundle while drawing to breakage a deviation from the straight path by means of a rotary member having pronounced but not cutting edges.

Through this procedure points of lowered resistance are momentarily created in the filaments to be broken as a result of the pronounced support and bending of the filaments by the projecting edges. The projecting edges also produce an impact as well as a momentary change in tension and in the deflection from the normal path of the filament which causes the filaments to break at such points of lowered resistance.

The invention will be better understood by referring to the following description, taken in connection with the accompanying drawings, in which specific embodiments are set forth for purposes of illustration.

In the drawings:

Fig. 1 is a diagrammatic view illustrating one embodiment of the invention;

Fig. 2 is a curve showing the improvement in length of the staple;

Fig. 3 is a detail view of a band having dihedrals to be used in the embodiment of Fig. 1;

Fig. 4 is a diagrammatic view similar to Fig. 1; and

Fig. 4a is a detail view of the band used in the embodiment of Fig. 4.

In Fig. 1 a bundle of filaments 1, advancing in the direction of the arrows, is supplied by a pair of feed rollers 1, 2 and is pulled by the pair of stretch rollers 3, 4 revolving at a speed that is a multiple of the speed of the rollers 1, 2. As a result of this the portion of the bundle 1 between rollers 1, 2 and rollers 3, 4 undergoes a stretching, which causes a breakage of the filament. The filament is made to deviate from the straight path by contact with a member 5 revolving on an axis 6, the edges of which member successively cause the filament to deviate with jerks. The breaks of filaments occur at the contact of the edges which produce weak points.

2

There is used for example a sliver of 1500 deniers, 1500 filaments of regenerated cellulose, having a tenacity of 2.25 grs. per denier.

The rollers 1, 2 have a peripheral speed of 90 cm./min., and the rollers, 3, 4 have a peripheral speed of 13.5M/min., giving a stretching ratio of 15 and producing a spun yarn of 100 d. on the average.

Without interposition of the member 5 and with suitable twisting a spun yarn is produced that has a tenacity of 1.35 g/d., viz. 60% of the tenacity of the initial bundle. The elongation to break of the spun yarn is 4.5%. When this spun yarn is moistened and when drying is done without tension a shrinkage of 9% is observed.

With the use of a member 5 of 20 mm. per side, having a speed of rotation of 65 R. P. M., viz. a peripheral speed of 5.2M/min., a spun yarn is obtained that has a tenacity of 1.80 g/d. or 80% of the tenacity of the initial bundle. The elongation to rupture or break is 6%. The shrinkage upon moistening followed by drying is 7%. The irregularities of long period are practically absent and the length of the fibers is more regular and the very short fibers are reduced in number.

Since the staple yarns obtained according to the usual staple process have a shrinkage of the order of 2 1/2%, the additional shrinkage is about 4 1/2% for the cracked spun yarn according to the invention, as against 6 1/2% for the spun yarn cracked without the rotating member.

Fig. 2 is a series of curves showing distribution of lengths of cut fibers—

Curve a—for a spun yarn obtained according to the invention; and
Curve b—for a spun yarn obtained without the revolving member.

Manifestly in the curve a there is a great proportion of longer fibers both in number and more particularly in weight.

In the example described use has been made of a square member 5 having a side of 20 mm. However, smaller or larger members can be used, for example of 10 mm. or of 30 mm. per side, revolving at appropriate rates of speed determined by the effect sought. It is not essential that the faces of the member 5 should be flat; for accentuating the edges they can be concave, the tangent planes according to an edge then making angles of less than 90° in the case of a square member; also convex faces can be used.

Members can also be used with a different number of edges, for example of 3 edges or of 5 edges. Even the use of a lenticular rotary member having only two edges can be considered, provided that the edges are not cutting, although distinctly pronounced and not rounded.

The peripheral speed of the rotary member 5 must be at least equal to the linear speed of the

filaments in contact with the edge, but a more regular run is obtained with speeds that are higher by as much as 45% to 60%.

If V^1 is the linear speed of the rollers 1 and 2
 V^2 is that of the rollers 3 and 4

V the speed on the average of the filaments over the member 5

C^1 the average distance between the edges of the member 5 and the point of departure of the bundle from the rollers 1, 2

C^2 the average distance between the edges of the member 5 and the point of entrance of the sliver to the rollers 3, 4.

One can write in first approximation:

$$V = V^1 + (V^2 - V^1) \times \frac{C^1}{C^1 + C^2}$$

For the speeds V^2 and V^1 given and for $C^1=8$ and $C^2=25$, which is a practical value, one obtained:

$$V = 0.90 + 12.6 \times \frac{8}{33} = \text{about } 4M$$

On the other hand for a speed or rotation of 65 R. P. M. the peripheral speed of the member 5 turns out at $65 \times 20^2 \times 2$. That is to say about 5.8M, which is 45% greater than the average speed of the filaments on the member 5.

However, the linear speed of the edges of the member 5 can be substantially greater than this figure. It can be 50% to 60% or more above without any drawback.

It is well to note that the revolving member can in certain cases be replaced with an endless moving band 22 bearing parallel transverse dihedrals 23 suitably spaced, as has been diagrammatically shown in Fig. 3. This device has the advantage of reducing the risk of winding broken thread onto the member. Another embodiment of the device described completely eliminates this risk. In this embodiment, shown diagrammatically in Figs. 4 and 4a, the revolving member is a cylinder 17 on which regularly spaced peripheral projections 13-16 are fixed, for example four in the form of teeth of gearings. In order to drive this cylinder use is made of a flexible band 18, having windows corresponding to the teeth.

In Fig. 4 the sliver 7 is supplied by the feed rollers 8, 9 and is taken up by the stretch rollers. The roller 9 drives tangentially the roller 12, which at the same time ensures quite a long contacting path for the bundle upon the roller 9 and thus eliminates the risk of slipping of the bundle upon the feed rollers.

Between the feed and stretch rollers the bundle is in contact with the four teeth 13, 14, 15 and 16 on the cylinder 27. The latter is driven by an endless belt 18, having (see Fig. 4a) openings 19, 19', 19'', 19''' registering with the teeth 13 to 16. The belt 18 passes further over the discharge pulleys 20, 21 and comes in contact likewise with the roller 12 which serves as a scraper to remove adhering fibers.

It is clear that the risk of winding of broken fibers on the rotary member 17 is totally eliminated in this case.

The belt 18 is driven by suitable means, not shown, and supports the bundle for a substantial distance between the member 17 and the roller 20. It is preferably driven at the same speed as the bundle or slightly faster than the bundle so as to aid in the drafting caused by the stretch rollers 10.

Although specific embodiments have been 75

shown for purposes of illustration it is to be understood that the invention may be adapted to various uses as will be apparent to a person skilled in the art.

5. What is claimed is:

1. An apparatus for converting a bundle of continuous filaments into a sliver of staple fibers by drawing to breakage, comprising a set of feed rollers and a set of stretch rollers, means driving said sets of rollers at successively greater speeds for stretching the bundle therebetween and a single rotary member having projecting non-cutting edges thereon disposed to contact one side only of the bundle and deflect said

15 bundle from a straight path of travel between said feed and stretch rollers, means driving said rotary member, said bundle being unconfined over said edges to permit uniform increase in the linear speed of said bundle between said feed rollers and said stretch rollers whereby said edges cause sudden changes in said deflection in the path of said bundle between said feed and stretch rollers and sudden changes in tension of the bundle adapted to localize the points in the filaments at 25 which breakage takes place due to the stretching force.

2. An apparatus as set forth in claim 1 in which a flexible belt is disposed over said member and has openings for said projecting non-cutting edges, said belt extending along the path of the bundle from the vicinity of said member to said stretch rollers to support the same and being driven at about the maximum speed of said bundle.

3. An apparatus, as set forth in claim 2, in which scraper means is provided to remove fibers from said belt prior to contact with said projecting non-cutting edges.

4. An apparatus as set forth in claim 1 in which the peripheral speed of the rotating member is intermediate the peripheral speeds of the sets of rollers.

5. An apparatus as set forth in claim 1 in which the peripheral speeds of the sets of rollers and the rotating member are related according to the formula

$$V = V^1 + (V^2 - V^1) \times \frac{C^1}{C^1 + C^2}$$

in which V^1 equals linear speed of the feed rollers, V^2 equals linear speed of the stretch rollers, V equals average speed of the filaments over the rotating member, C^1 equals average distance between the edges of the rotating member and the nip of the feed rollers, and C^2 equals average distance between the edges of the rotary member and the nip of the stretch rollers.
